DIFFUSER WITH A DETACHABLE DEFLECTOR MEMBER

Harry Daninhirsch, Danbury, Conn., assignor to Connor Engineering Corporation, Danbury, Conn., a corporation of New York

Application November 23, 1953, Serial No. 393,887

7 Claims. (Cl. 98—40)

This invention relates to outlets for ventilating or air-conditioning devices, and particularly to a ceiling diffuser for supplying air to rooms and other inclosures. It is an object of the invention to provide an outlet of this character provided with a deflector member to be secured in place as to permit of its ready removal for cleansing or for any other purpose.

It is another object of the invention to provide means by which the deflector member can be applied over an outlet in a manner to enable it to be securely, yet removably retained in place, and without the use of screws, bolts or other separable fastening elements likely to become lost during the removal or replacement of the deflector member.

It is still another object of the invention to provide a deflector member for placement over an air outlet, which member will be maintained in place by spring elements or spring clips, and which are arranged to engage and maintain the deflector member in any one of a number of positions to thereby enable an outlet orifice with which the deflector member is provided to be located according to the desired directional flow of air from the outlet.

A still further object of the invention is to provide an air outlet with a deflector member that is removable and replaceable without the use of tools, thereby promoting periodic removal of the deflector member and cleansing of the outlet and interior of the deflector member.

With these and other objects to be hereinafter set forth in view, I have devised the arrangement of parts to be described and more particularly pointed out in the claims appended hereto.

In the accompanying drawing, wherein an illustrative embodiment of the invention is disclosed,

Fig. 1 is a vertical sectional view through the air outlet and deflector member in the form of an inclosing hood, showing a portion of the hood, at the left of the Figure, broken off;

Fig. 1a is a vertical sectional view through the broken-off part of the hood;

Fig. 2 is a sectional view, taken substantially on the line 2—2 of Fig. 1, looking in the direction of the arrows;

Fig. 3 is a sectional view, taken substantially on the line 3—3 of Fig. 1, looking in the direction of the arrows;

Fig. 4 is a sectional view, taken substantially on the line 4—4 of Fig. 1, looking in the direction of the arrows; and

Fig. 5 is a view similar to Fig. 4, but taken on the line 5—5 of Fig. 1, looking in the direction of the arrows and showing the hood in engagement with the retaining clip.

Referring to the drawing, and particularly to Fig. 1 thereof, 1 indicates an annulus, ring member or plate adapted to be secured to the outlet of an air supply duct by suitable fastening elements, such as screws extended through the radial flange 2 of the ring member. The flange 2 is formed with a depressed annular channel or seat 3 which receives a soft and compressible washer or

2

gasket 4, composed of sponge rubber or some material of substantially similar characteristics. A downwardly-extended annular flange 5 surrounds the central outlet opening 6 in the ring member or plate 1, and secured on and extending downwardly from the flange 5 is a perforated sleeve or cylinder 7. The sleeve or cylinder 7 is perforated for its entire area and is thus of a foraminous nature so that the air may flow through it.

The hood 8 for the outlet is of cup-shaped frustro-conical formation and has a closed bottom 9 and side wall 10, the side wall and bottom being imperforate, except for a slot-like air outlet orifice 11, surrounded by an edging or trim 12 of a plastic material such as polystyrene or other suitable material. In the interior of the hood, and maintained on the bottom 9 thereof, is sound-reducing material, such as fibre-glass 13. Provided at the top of the hood 8 is an annular closure ring 14, which is provided at its peripheral edge with a downturned flange 15 fitting over the top edge of the side wall 10 of the hood and attaching the closure ring 14 to the hood. The closure ring 14 is formed with a depressed annular seat 16 on which is provided a washer or gasket 17 composed of felt or similar material. When the hood 8 is fitted in place, as is seen at the right in Fig. 1, it will be noted that the washer or gasket 17 is interposed between the upper face of the closure ring 14 and the under surface of the plate 1. At the same time, the raised inner flange 18 on the closure ring 14 fits under the part 19 of the ring member 1, thus centrally positioning the hood 8 with respect to the ring member 1.

Vertically regulatable within the perforated sleeve or cylinder 7 is a disk-shaped damper 20, provided on its periphery with a washer or sealing member 21, which can be of plastic material such as polystyrene or the like, and which establishes a close but sliding contact with the inner surface of the sleeve or cylinder 7. Centrally positioned in the damper 20 and held against axial movement relatively thereto, is a rotatable, internally-threaded hub member 22 threadable on the adjusting spindle 23 rotatably secured in the bottom 9 of the hood 8. It will be noted that the bottom of the hood is confined between the head 24a and disk 25 of the spindle 23 so that while the spindle 23 can be rotated within the hood by engagement of a suitable tool with a slot in the head 24a, the spindle will not become detached from the hood. As the spindle is rotated, it will be clear that the threadable connection between it and the hub 22, rotatively attached to the damper 20, will cause the damper to be raised or lowered as required to thereby regulate the flow of the air through the perforated cylinder or sleeve 7. The cross pin 36 in the spindle 23 prevents inadvertent separation of the spindle from the hub 22.

Secured adjacent to the inner end of the ring member 14 is an arcuate perforated plate 24 so that this plate is carried by and is removable with the hood when the hood is detached from the ring member 1 in the manner to be now described. It will be noted that the perforated plate 24 is located in registry with the outlet orifice 11. When the hood is fitted in place on the plate 1, the perforated plate 24 is interposed between the air orifice 11 and the sleeve 7 as seen at the right in Fig. 1.

The means for securing the hood 8 in position with respect to the ring member 1, and as shown at the right in Fig. 1, consists of a plurality of spring members or clips 35 secured to the ring member 1 in the manner shown in Figs. 4 and 5. It will be therein noted that each clip includes a resilient arched finger 26 having an integral, vertical leg portion 27, which extends upwardly through a slot 28 in the ring member 1. The clip is also formed with an integral tab portion 29 which is disposed flatly against the upper face of the ring member or plate 1 and is secured thereto by a single rivet 30 or equivalent.

fastening element. A single fastening element is all that is required to thus attach each clip in position, since the leg portion 27, fitting through the complementary slot 28, prevents rotation or swiveling movement of the clip.

Provided in the closure ring 14 is a plurality of spaced slot-like apertures 31. Each of these apertures is of a size to permit the finger portion 26 of any one of the clips to be inserted through it. As shown in Fig. 4, the hood is lifted vertically, with four of the apertures 31 registered with the four clips 35, and the fingers 26 of the clips are then inserted through the apertures 31. The hood 8 is then given a slight rotative movement and the fingers 26 will engage beneath the closure ring 14 to thereby hold the hood securely attached to the ring member 1 over the duct outlet. When the hood is rotated in the manner described, it will be noted that the vertical leg portion 27 of each of the clips 35 will act as a stop to thereby limit the rotative movement of the hood and also indicate that the hood has reached its position of firm attachment to the ring member 1. It is to be observed that since the fastening tab 29 of each of the clips 35 is disposed on the top side of the ring member 1, it will not be reached or contacted by the ring member 14 when the hood is being attached, and thus the possibility of the clips becoming pried off or loosened by repeated placement of the hood in position, will be avoided.

As will be seen in Fig. 2, the closure ring 14 of the hood is formed with eight of the apertures 31, while four clips 35 are provided. This arrangement is such that it enables the user of the device to place the hood in various positions on the plate 1 to thereby extend the outlet orifice 11 in any desired direction and thus direct the air flow accordingly. By selection of the required apertures 31 for engagement with the clips, the directional control of the air flow will be had.

From the foregoing, the operation of the described structure will be readily understood. In placing the hood in position, it is raised until the fingers 26 of the four clips extend through the required four apertures 31, whereupon the hood is rotated slightly until the fingers 26 engage under the parts of the ring member 1 adjacent to the apertures, in the manner shown in Fig. 5. The spring clips, thus engaging the hood, will not only firmly hold it in position, but avoid the possibility of rattle and noise. This is of great importance as many of the outlet devices or diffusers to which this invention is applicable have been designed to operate at relatively high discharge velocities ranging between 3000 F. P. M. to 8000 F. P. M. At these high velocities the deflector member tends to "chatter," which not only generates an objectionable noise, but the vibration also causes undue wear upon the parts. The spring clips according to this invention serve to cushion the deflector member against the outlet plate and thus tend to counteract any possible "chattering action" of the deflector member. While the hood is in place the damper 20 can be easily regulated by rotative movement of the spindle 22. The removal of the hood for cleaning of it as well as the other parts of the outlet is had by merely twisting the hood slightly to enable the clips to be passed through the apertures 31 and the hood then lowered. Since a substantial number of the apertures 31 are provided in the closure ring 14, it will be apparent that any desired four of them may be employed for engagement with the clips and thus the outlet orifice 11 can be disposed for the emission of air in any required direction.

Having described one embodiment of the invention, it is obvious that the same is not to be restricted thereto, but is broad enough to cover all structures coming within the scope of the annexed claims.

What I claim is:

1. In a device of the character described, an annular plate for attachment to the outlet of an air duct, a perforated sleeve attached centrally of the plate and forming an air passage projecting from the plate, a cup-shaped

hood fitted over the sleeve, a damper carried by the hood and adjustable up and down within the sleeve, the hood having a side wall formed with an air orifice, an arcuate perforated plate disposed within the hood and interposed between the air orifice and the perforated sleeve, said arcuate perforated plate being carried by and removable with the hood, the hood having an annular top flange supporting the perforated plate, said top flange being provided with a plurality of apertures arranged in a circle, and the annular plate having spring clips arranged in a circle and extending through said apertures and engaging against the under side of the top flange of the hood.

2. In a device of the character provided for in claim 1 wherein the apertures in the top of the hood are greater in number than the number of spring clips to permit the hood to be positioned in a manner to enable the air orifice to face in any one of a number of directions, said clips being caused to engage with or become disengaged from the annular plate by rotative movement of the hood relative thereto.

3. In a device of the character described, an annular plate attached to the outlet of an air duct, a hood fitted thereover and having an apertured top, and means for detachably connecting the hood to the plate comprising a series of spring clips fastened on the plate and circularly arranged and extending through the apertures in the top flange of the hood and engaging against a face of the top of the hood adjacent to said apertures by rotative movement of the hood about a vertical axis.

4. In a device of the character provided for in claim 3, wherein each clip consists of a resilient finger portion engaging against a face of the top flange of the hood, an integral leg portion extending through a slot in the annular plate, and a tab portion disposed on the upper face of the plate and attached to said plate, the leg portion of the clip constituting an abutment to limit rotation of the hood when the hood is being placed in engagement with the clips.

5. In a device of the character described, an annular plate attached to the outlet of an air duct, a perforated sleeve attached to said annular plate and forming a tubular perforated air passage, a hood for fitment around the sleeve, said hood having a side wall provided with an air outlet, spaced spring clips provided on the annular plate, the hood being provided at one end with an annular flange for facial contact with the annular plate, the flange being provided with openings corresponding at least to the number of spring clips and shaped to permit the passage of the spring clips through them, the clips and openings therefor being circularly arranged, the clips being each provided with a finger portion taking under parts of the flange to thereby attach the hood to the flanged plate when the clips are inserted through the openings in the flange and the hood is rotatively moved about its axis.

6. In a device of the character described, an annular plate attached to the outlet of an air duct, a perforated cylindrical sleeve attached to and depending from the annular plate and forming an air passage leading from the duct outlet, a cup-shaped hood for fitment over the annular plate and around the sleeve, a damper carried by the hood and adjustable within the sleeve, the hood having a side wall provided with an outlet opening, an arcuate perforated plate located within the hood and interposed between the perforated sleeve and outlet opening, the annular plate being provided with a plurality of spring clips arranged in a circle, each clip having a finger extending along the under side of the annular plate, the hood having a flange formed with a plurality of slots conforming at least in number to the clips and through which the fingers of the clips can be extended to take under the flange on rotative movement of the hood about a vertical axis, to thereby attach the hood to the annular plate.

7. In a device of the character described, a plate attached to the outlet of an air duct, a hood for attachment

to the plate, said plate having a plurality of circularly-arranged spring clips having fingers exposed on the face of the plate, the hood having an upper flange for facial disposition against the plate, said flange being provided with apertures arranged circularly for registry with the fingers of the clips and adapted to engage therewith by placement of the flange against the plate and rotatively moving the hood, the hood having a side air outlet, the apertures in the flange of the hood being greater in number than the clips so that a selected number of said 10 apertures can be used to engage with the clips to thus

position the air outlet in any one of a number of selected positions.
